(57) CLAIM

The ornamental design for a shoe, as shown and described.

DESCRIPTION

FIG. 1 is a bottom front perspective view of a shoe showing my new design; and,

FIG. 2 is a bottom view thereof.

The broken line immediately adjacent to and surrounding the photographic area defines the peripheral bounds of the claimed design and forms no part thereof. The non-photographic white regions within the peripheral bounds form no part of the claimed design. The broken lines depicting the remainder of the shoe form no part of the claimed design.
